Graham Crosby

UNITED STATES PATENT OFFICE.

CHARLES KULMAN, OF BROOKLYN, NEW YORK, ASSIGNOR OF ONE-HALF TO ALBERT E. THOMAS, OF WEST NEW YORK, NEW JERSEY.

SCOW.

1,397,527.

Specification of Letters Patent.

Patented Nov. 22, 1921.

Application filed May 16, 1921. Serial No. 470,140.

To all whom it may concern:

Be it known that I, CHARLES KULMAN, a citizen of the United States, and resident of Brooklyn, in the county of Kings and State 5 of New York, have invented certain new and useful Improvements in Scows, of which the following is a specification.

My invention relates to improvements in dumping scows and more particularly to a 10 scow adapted to dump floating matter. The main object of the invention is to provide a scow which will not only satisfactorily dump heavy materials which will sink through trap doors in the bottom of the 15 scow, but will also satisfactorily dump light floating matter. Further and more specific objects, features and advantages will more clearly appear from the detail description given below taken in connection with the ac- 20 companying sheet of drawings which form a part of this specification. In the drawings, Figure 1 is a longitudinal vertical section through a scow embodying my improvements in a preferred form and Fig. 2 is an 25 end view of the same.

Referring to the drawings, 3 indicates a scow having a central opening divided into a plurality of compartments 4 by means of transverse partitions 5 and forward and rear 30 end walls 6. The scow is built out around these compartments forming water tight buoying chambers 7 at the ends and similar chambers 8 along the sides. The partitions 5 and 6 do not extend down to the bottom of 35 the scow but the bottom of the partitions is above the water line when the scow is light, this water line being indicated at 9. Below the compartments 4 the scow is provided with trap doors 10 hinged as at 11, to the 40 bottom of the side walls of the scow and adapted to be operated by chains 12 passing over winches 13 so that the doors may be dropped and opened to dump out material from the compartments. These serve well 45 for dumping heavy material which will sink but much difficulty has been encountered in dumping floating material from such scows because it will not sink through the bottom trap doors. I, therefore, provide openings 50 14 through the forward and rear end walls of the scow, the tops of which are above the water line when the scow is light; so that any floating matter remaining in the scow will be flushed out through the opening in

the rear wall of the scow as the scow is 55 moved through the water. By having such openings in both ends the cleaning of the scow from floating matter may be accom- plished by moving the scow in either direc- 60 tion. When loading and until it is desired to dump the scow the end openings 14 may be closed by trap doors 15 hinged at 16 to the side walls and operated by chains 17 passing over winches 18. The chains pref- 65 erably pass through pipes 19 set in the end chambers 7 and so that the chambers 7 are still kept water-tight. When it is desired to flush out floating matter the winches 18 are operated to release the doors 15 causing them to swing downwardly and outwardly about 70 the pivots or hinges 16 located along the side edges of the doors so that the end open- ings are thereby fully opened.

While I have described my improvements in great detail and with respect to a pre- 75 ferred form thereof, I do not desire to be limited to such details or form since many changes and modifications may be made and the invention embodied in widely different forms without departing from the spirit and 80 scope thereof in its broader aspects.

What I claim and desire to secure by Let- 85 ters Patent, is:

1. A dumping scow having an opening through the rear wall thereof, out through 85 which material in the scow may flow and a door for said opening hinged to swing down- wardly and outwardly to open the opening.

2. A dumping scow having an opening through the rear wall thereof, out through 90 which material in the scow may flow, the top of said opening being above the water line when the scow is light and a door for said opening pivoted at one of its side edges to 95 swing outwardly to open said opening.

3. A dumping scow having a plurality of transverse partitions therein and an opening through the rear wall of the scow out through which material in the scow may 100 flow, the top of said opening and the bot- tom of said partitions being above the water line when the scow is light and doors for said opening, each door being hinged at one of its side edges to swing downwardly and outwardly to open said opening.

4. A dumping scow having openings through the forward and rear walls of the scow respectively, out through which mate- 105

rial in the scow may flow and doors for closing said openings said doors being hinged to swing downwardly to open said openings.

5. A dumping scow having an opening through the rear wall thereof, out through which material in the scow may flow, the top of said opening being above the water line when the scow is light and trap doors for closing said opening said doors being hinged 10 to swing outwardly to open said opening.

6. A dumping scow having bottom trap doors for dumping and an opening through an end wall of the scow out through which material in the scow may flow, and means 15 for closing said opening said means includ-

ing a door hinged to swing downwardly and outwardly to open said opening.

7. A dumping scow having bottom trap doors for dumping and openings through the forward and rear walls of the scow respectively, out through which material in the scow may flow, and doors for closing said openings, the top of said openings being above the water line when the scow is light and said doors being pivoted to swing outwardly away from the body of the scow. 20 25

Signed at New York, in the county of New York, and State of New York, this 13th day of May, A. D. 1921.

CHARLES KULMAN.
